UNITED STATES PATENT OFFICE

HARRY V. HAIGHT, OF SHERBROOKE, QUEBEC, CANADA, ASSIGNOR TO INGERSOLL-RAND COMPANY, OF JERSEY CITY, NEW JERSEY, A CORPORATION OF NEW JERSEY

DUAL UNLOADING SYSTEM

Application filed January 6, 1931. Serial No. 506,925.

This invention relates to compressor unloaders, and the objects of the invention are to enable the compressor to be quickly and conveniently unloaded both on starting and 5 stopping and also to be unloaded or reloaded as required during operation, depending on the load.

In accordance with this invention the compressor is provided with a plurality of 10 unloading systems arranged to unload the compressor either by one system or the other, but incapable of reloading the compressor unless both systems tend to reload. One system or the other may unload the compressor, 15 but the operation of both systems is required to reload the compressor.

In this way one system or the other may be selected for the unloading operation, and one system may be an automatic system 20 while the other is manually controlled. A controlling valve is preferably provided for automatically bringing one system or the other into operation and another valve is provided for selecting the system for operation. The automatic controlling valve also 25 prevents the reloading of the compressor unless both systems are operative for reloading.

The drawings illustrate preferred forms 30 of the invention, in which

Figure 1 is a diagrammatic representation partly in vertical section and partly broken away, showing the dual unloading system applied to one cylinder of a compressor, and.

Figure 2 is a similar view of the dual system applied to the two cylinders of a compound compressor.

Referring to the drawings and at first 40 more particularly to Figure 1, the compressor cylinder A has the piston B driven from the belt wheel C by means of an electric motor (not shown). The air enters at the intake D and is discharged through the discharge pipe E into the receiver F in the usual manner. The cylinder is provided with the inlet valves G and the discharge valves H. In this instance the inlet valves 45 are provided with valve openers in the form of pistons J operating in the cylinders K

and these pistons have fingers L for holding the inlet valves away from their seats when pressure fluid is supplied to the cylinders K through the pipes O. These valve openers constitute unloading devices for unloading the compressor.

Two unloading systems are provided for operating the unloading devices and one system includes the valve parts associated with the valve casing P and electro-magnet Q 55 controlled from the switch R and the other system includes the valve mechanism associated with the valve casing S. Both systems are controlled by the automatic controlling valve contained in the casing T and 60 a manually controlled valve in the casing U enables either one system or the other to be selected for unloading the compressor. As will be explained, the compressor cannot 65 be reloaded until both systems tend to reload the compressor or are in condition for the 70 reloading operation.

Referring to the unloading system controlled by the electric switch R, it will be 75 observed that when the electro-magnet Q is deenergized, the weight V will move the core W to its lowermost position as shown in Figure 1 in which case the lever X will be rocked on its pivot Y and the lever arm Z will force the pin a upwardly and cause the ball valve b to be seated while the pin c will force the ball valve d away from its seat against the tension spring e. Pressure fluid from the receiver F will then pass through the pipe f and with the manually controlled 80 valve g in the position shown in the valve casing U, the receiver pressure will pass through pipe h to the valve casing P, thence through the pipe i to the valve casing T of the controlling valve. The ball valve r 85 in the valve casing T will be forced to its seat as indicated in Figure 1 and pressure fluid will pass through the apertures s in the valve cage and through the pipe t to the two pipes O leading to the unloading device cylinders K. The inlet valves will be held away from their seats and the compressor cylinder will be unloaded.

The manually controlled valve U when 90 in the position shown in Figure 1 prevents 95 100

fluid pressure from the receiver F from passing through the pipe f to the pipe u leading to the auxiliary valve casing S so that the system of unloading including the valve in 5 the casing S is inoperative for unloading the compressor. This is for the reason that pressure is required to lift the piston v forming the valve in the casing S which piston is held to its seat by the spring w, 10 compressed between the head x on the stem y and the end of the sleeve z. There is sufficient clearance between the sleeve z and stem y to form a vent leading to atmosphere at the vent port 3. The pipe 4 connects the side 15 of the cylinder S with the valve casing T of the automatic controlling valve so that the left hand side of the ball valve r as shown in Figure 1 is vented through the pipe 4 to atmosphere through the valve casing 20 S and through the vent 3. The unloading system including the valve casing S and valve v is thus in condition to vent the unloading device cylinders K and permit re-loading of the compressor when the ball 25 valve r is removed from its seat.

To reload the compressor, the electric switch R is closed and the magnet Q energized which rocks the lever X and releases the ball valve b so that this valve is removed 30 from its seat and the ball valve d becomes seated, thus shutting off the supply of pressure fluid to the automatic valve in the casing T and opening said valve casing through 35 the pipe 5 either to atmosphere or to the inlet D as shown in the drawings. The backs of the pistons J in the unloading device cylinders K are thus relieved of pressure both through the valve casing P and through the valve casing S and the compressor cylinder 40 is reloaded. The electric switch R may be connected to be operated automatically from the circuit including the motor which drives the compressor so that the compressor is unloaded on starting and stopping, but these connections are not shown 45 as they are the usual start and stop connections.

Let it be assumed that the valve g is turned to the opposite position by turning 50 the handle 6 counter-clockwise, in which case pressure fluid will be cut off between the pipes f and h and pressure fluid will be supplied from the receiver F through the pipe U to the valve piston v in the casing S of the 55 auxiliary valve and when the pressure in the receiver is sufficient this valve v will be raised from its seat 7 and the upper end will be seated on the seat 8. The pressure fluid will then pass through the pipe 4 to the automatic controlling valve in the casing T, which will unseat the ball valve r and pressure fluid will be supplied through the pipe t and pipes O to the backs of the pistons J of the unloading devices which will unload 60 the compressor. A sufficient reduction of 65

pressure in the receiver F will cause the valve v in the casing S to be retracted into the initial position shown in the drawings, which will open the pipe 4 to the vent 3 but the reloading operations cannot take place 70 until the valves in the casing P are in condition for reloading since the ball valve r must assume a position permitting the free venting of the pipes o and t. This condition is brought about by closing the switch R, raising the lever X and lowering the pin a so that the ball valve b opens communication between the pipe g and the vent pipe 5. The ball valve r will then assume a neutral 75 position and the venting relief of pressure 80 behind the unloading device pistons J may take place.

In accordance with the invention so far described it will be observed that the position of the manual valve g determines the 85 selection of the unloading system which is to operate the unloading devices and unload the compressor. In order, however, that the compressor may be reloaded, both unloading systems must be in reloading conditions or must tend to reload before the re-loading can take place.

In Figure 2 the invention is shown applied to a compound compressor having a low pressure cylinder 9 and the high pressure cylinder 10. The pistons 12 and 13 are driven from the crank shaft 14 in any suitable manner. The cylinders are provided with the usual inlet and discharge valves G and H and the inlet valves are provided with the valve lifters L carried by the pistons J in the cylinders K thus forming unloading devices as in Figure 1. These unloading devices J, K, L form free air unloading devices, so called because the inlet valves are held open and permit air to pass freely in and out of the cylinders for unloading purposes. The air enters the low pressure cylinder at the inlet 15 and is discharged through the outlet 16 and after 95 passing through the intercooler (not shown) enters at the inlet 17 of the high pressure cylinder and is discharged from the discharge outlet 18 of the high pressure cylinder 100 to the receiver tank F shown at the top of Figure 2, it being understood that there is a connection between the discharge outlet 18 of the high pressure cylinder and the receiver F not shown for simplicity.

In addition to the free air unloading devices J, K, L the cylinders are provided with clearance unloaders and in this instance clearance chambers 19 and 20 are shown in the cylinder heads 21 and 22 at the crank 115 ends of the cylinders. These clearance chambers 19 and 20 are controlled by the clearance valves 23 having plunger heads 24 operating in the valve cylinders 25. Similar valve cylinders 25 are shown in the cylinder heads at the head ends of the com- 120 125 130

pressor adapted to contain clearance valves for controlling clearance chambers in the head ends.

One unloading system is provided for 5 operating the free air unloaders or valve lifters L and another unloading system is provided for operating the clearance valves 23 in both the head and crank ends of the cylinders. These two unloading systems are 10 so devised and arranged that either system may be used for unloading the compressor, but the compressor cannot be reloaded until both systems are in reloading condition.

An automatic regulator of any suitable 15 or usual type, as for instance that shown in United States Patent No. 1,588,257 granted June 8, 1926 to Chester W. Metzgar for Compressor unloader may be provided for automatically controlling the free air unloaders 20 L. This regulator is shown partly broken away at the upper left hand corner of Figure 2 and comprises a lever 26 pivoted at 27 on a casing 28 which contains a diaphragm 29 subject to receiver pressure through the pipe 30.

25 A pin 31 bearing against the lever 26 is actuated by the diaphragm 29 to raise and lower said lever. The weight 32 on the lever may be adjusted along its length for balancing purposes.

30 The valve stem 33 of a pilot valve 34 is pivoted at 35 to the lever 26 and the movement of the pilot valve 34 controls main valves 36 in the regulator valve casing, only one of said valves 36 being shown. The 35 valve chamber of the pilot valve 34 is supplied with pressure fluid from the receiver F through the pipe 37 and the lower end of said valve chamber is vented through the pipe 38. The valve chambers of the 40 main valves 36 are supplied with pressure fluid from the diaphragm chamber through the passage 39.

The operation of the automatic regulator 45 is fully set forth in Patent No. 1,588,257 and will only be briefly described. Assuming that the pilot valve 34 is in its lower-most position as indicated in Figure 2, all the valves 36 of which there are two in this case, will be in their right hand position 50 as indicated by the valve 36 shown in section because pressure fluid entering through the pipe 37 passes through the passage 40 to the main valve 36 and the opposite end of said valve is vented through the passage 41 to atmosphere through the upper open end 42 of the pilot valve casing. Pressure fluid can then pass through the passage 39 around the valve 36 and through the passage 43 to the pipe 44 to the casing of the controlling valve 45 and assuming that the ball valves 46 and 47 in the casing 45 are in neutral position owing to the introduction of pressure fluid at each end of the casing 55 the pressure fluid will pass on around valve

46 and through pipe 48 and branch pipe 49 to the cylinders 25 of the unloading valves 24 in the heads of the two compressor cylinders holding said unloading valves to their seats.

70

Pressure fluid is supplied to the right hand end of the valve casing 45 under such conditions through the pipe 50 and through the valve casing P which is similar to the valve casing P shown in Figure 1 and contains the same ball valves b and d. Since the switch R is open the electro-magnet Q is deenergized and the ball valve b is seated while the valve d is unseated and pressure fluid is supplied from the branch pipe 51 to the casing P and around the ball valve d to the pipe 50, thus as described introducing pressure fluid at the right hand end of the valve casing 45. This pressure fluid may also pass through the pipe 48 to the clearance valves.

80

In a similar manner pressure fluid is being supplied from the regulator through the pipe 52 to and through the valve casing 53 similar to the valve casing 45 and through the pipe 54 and branch pipe 55 to the clearance valves at the crank end of the high pressure cylinder and the head end of the low pressure cylinder so that these valves are held to their seats in loading position. 90 Pressure fluid is also supplied to the right hand end of the valve casing 53 through the pipe 56 leading to the valve casing P' which is similar to the valve casing P and the parts in said valve casing are in similar position. 100 Pressure fluid is led to the valve casing P' through the pipe 57 connected to the pipe 30, and in the position of the parts in Figure 2 passes around the ball valve d to the pipe 56.

105

110 Pipe 37 is continued from the point at which it leaves the casing of the automatic regulator and is connected to the casing T' of an automatic controlling valve actuated by an electro-magnet Q' having the weighted core W', suspended from the lever arm 58 pivoted at 59 on the valve casing and having the arm 60 for actuating the pin 61 extending into the valve casing. The ball valves 62 and 63 are separated by the pin 64 and a spring e bears on the ball valve 63. A pipe 65 leads from the casing T' to the unloader valve casings K on the cylinders which contain the pistons J for the inlet valve openers, and when pressure fluid is supplied through the pipe 65 the inlet valves G are lifted from their seats for unloading both cylinders.

115

120 The valve casing T' is provided with the vent 66 and in the position of the parts shown in Figure 2 the pipe 65 is vented to atmosphere through the pipe 66 because the switch R' is open the magnet Q' is deenergized and the weighted core W' has rocked the lever arm 58 to permit the ball valve 62

125

130

to open. Upon closure of the switch R' which energizes the magnet Q' the core W' will be retracted, the ball valve 62 will be forced to its seat and the ball valve 63 lifted 5 from its seat so that pressure fluid will be supplied through the pipes 37 and 65 to operate the inlet valve lifters J .

It is to be understood that the automatic regulator having the pivoted lever 26 shown 10 at the upper left hand corner of Figure 2 in conjunction with the automatic valves in the valve casings 45 and 53 and the pipes and connections leading to the clearance valves 23 constitute one system of unloading, while 15 the automatic valve in the casing T' in combination with the inlet valve lifters J constitutes another system of unloading. The switch R controls electro-responsive devices Q and Q' in both systems and the arrangement and construction is such that either one 20 system or the other may unload the compressor but both systems are required for re-loading the compressor.

In the operation of the apparatus, let it 25 be assumed first, that the parts are all in the position as indicated in Figure 2 in which case the compressor is loaded. Upon an increase of pressure in the receiver F beyond a certain degree the pilot valve 34 will 30 be lifted and in the first step will open the passage 40 shown in full lines to the vent 38 and will supply fluid pressure from the pipe 37 through the passage 41 shown in full lines so that the valve 36 will be moved 35 to the left and the passage 43 will be placed in communication with the vent 67. The pipe 44 leading to the valve casing 45 will thus be vented to atmosphere and the pressure fluid from the pipe 50 in the right hand end of the casing 45 will shift the ball valves 46 and 47 so that the pipe 48 leading 40 to two of the clearance valves 23 at opposite ends of the compressor cylinders will be vented to atmosphere. The clearance valves 45 will open and the compressor will be partially unloaded. When the pilot valve 34 of the regulator moves upwardly another step, a similar action will occur in connection with the valves in the casing 53 and the pipes 54 and 52 will be vented to atmosphere so that the other clearance valves 23 45 will open and further unload the compressor. It is to be understood that there may be as many steps of clearance unloading provided as desired, only two being shown for purposes of illustration.

To bring the second system of unloading into operation, the switch R' is closed which 50 energizes the electro-magnet Q' , raises the core W' , rocks the lever 58, closes the ball valve 62, opens the ball valve 63 and permits pressure fluid to pass from pipe 37 around ball valve 63 to pipe 65 and actuate 55 the valve lifters J which hold the inlet

valves off their seats and produces unloading of the cylinders.

The compressor cylinders may be partially reloaded by reopening the switch R' which will restore the parts in the valve 70 casing T' to the position shown in the drawings, but the compressor cannot be completely reloaded unless the regulator arm 26 returns to reloading position by reduction of pressure in the receiver F . On starting 75 for instance, the switch R may be closed which will energize the magnets Q , raise the core W , rock the levers X and permit the ball valves in the casings P and P' to change position so that the pipe 50 and 56 80 are vented through the vents 5 around the ball valves b . Pressure fluid in the pipes 44 and 52 will force the valves in the casings 45 and 53 to the right as the drawing is viewed so that the pipes 48 and 54 will be 85 vented and the clearance valves will open and unload the compressor. The switch R may be automatically operated as usual from the starting switch on the motor, but these connections are not shown as they are of 90 usual and standard construction.

I claim:

1. In a compressor, having unloading devices, a plurality of systems for controlling said devices, means for bringing one control system or the other into operation to unload the compressor, and means requiring the operation of both systems to reload the compressor.

2. In a compressor having an unloading 100 means, the combination of two systems controlling the unloading means and interconnections between the systems so arranged that either system may operate to unload the compressor without the other, and maintain 105 an unloaded condition until both systems operate to reload.

3. In a compressor, the combination of unloading devices for the compressor, two control systems for actuating said devices, and 110 a controlling valve common to both systems so designed that if either system tends to unload the compressor unloading will take place, but the compressor will be maintained in unloaded condition unless both 115 systems tend to reload.

4. In a compressor, the combination of one set of unloading devices for the compressor, two control systems for actuating said devices, and a controlling valve for automatically bringing one system or the other into operation for unloading the compressor, and maintaining the compressor in unloaded condition unless both systems tend to reload.

5. In a compressor, the combination of 120 one set of unloading devices for the compressor, two control systems for actuating said devices, a controlling valve for automatically bringing one system or the other into operation for unloading the compressor 125

and maintaining the compressor in unloaded condition unless both systems tend to reload, and means for selecting one system or the other for unloading.

5 6. In a compressor, the combination of one set of unloading devices for the compressor, two pilot systems for actuating said devices, a controlling valve for automatically bringing one system or the other into operation for unloading the compressor and maintaining the compressor in unloaded condition unless both systems tend to reload, and means for selecting one system for unloading while rendering the other inoperative for unloading.

10 7. In a compressor, the combination of one set of unloading devices for the compressor, two pilot systems for actuating said devices, a controlling valve for automatically bringing one system or the other into operation for unloading the compressor and maintaining the unloaded condition unless both systems tend to reload, means for selecting one system for unloading while rendering the other inoperative for unloading, and means for restoring the other system to loading operation so that both systems will tend to reload.

15 8. In a compressor, the combination of one set of unloading devices for the compressor, two pilot systems for actuating said devices, one system operating to automatically unload and reload the compressor, the other system being manually controlled, and a controlling valve for automatically bringing one system or the other into operation according to the system selected, and means for selecting one system or the other for operation as an unloader, said controlling valve maintaining the compressor in unloaded condition unless both systems are operative for reloading.

20 9. In a compressor, means to reduce the load and a plurality of control means independent of each other for actuating the load reducing means but interdependent for releasing said load reducing means.

25 10. In a compressor, means to unload the same, and a plurality of independent control means to actuate said unloading means, and additional means to maintain the unloaded condition until all the control means cooperate to reload.

30 11. In a compressor, means to unload the same, a plurality of independent control means for actuating the unloading means, and additional means to limit the reloading activity of one control means until the cooperation of all control means is effected.

35 12. In a compressor, means to unload the same, a plurality of independent control means for actuating the unloading means, and additional means cooperating with the control means to maintain the compressor in unloaded condition until all of said con-

trol means are placed in reloading position.

13. In a compressor having a plurality of unloading means, a plurality of independent control means for selectively actuating said unloading means, and further means to maintain the compressor in unloaded condition until all of the control means are in position to reload.

70 14. In a compressor having a plurality of unloading means, a plurality of independent control means for selectively actuating said unloading means, and further means cooperating with said control means to maintain the compressor in unloaded condition until all of said control means are in position for reloading.

75 15. In a compressor having a cylinder equipped with clearance control, a plurality of means for unloading said compressor, a plurality of independently operable control devices for selectively actuating said unloading means, and further means to maintain the compressor in unloaded condition until all of the control devices are in position for reloading.

80 16. In a compressor having valves, means to hold a valve open, pressure responsive means to actuate said valve holding means, electro-magnetic means independent of said pressure responsive means to actuate said valve holding means, both said actuating means being coactive to the extent that the cooperation of both is required to permit closing of the valve.

85 In testimony whereof I have signed this specification.
